POWER CONTROLLING MEANS FOR
WINDMILLS

Luke S. Stripling, Amarillo, Tex.

Application February 3, 1937, Serial No. 123,900

17 Claims. (Cl. 74—41)

This invention relates to windmills and other like devices and has special reference to power controlling means for windmills.

One important object of the invention is to provide an improved general construction of means whereby the action of a windmill may be rendered uniform and independent of the fluctuations in speed which are occasioned by fluctuations in wind velocity.

10 A second important object of the invention is to provide a novel pendulum actuated apparatus for attachment to a windmill of ordinary construction, which apparatus will effectively prevent fluctuations in the speed of operations performed by the windmill.

15 A third important object of the invention is to provide a novel apparatus of this character forming a species of governor for a windmill.

20 A fourth important object of the invention is to provide a pendulum controlled windmill governor of novel construction and wherein the pendulum may be varied in length to control the timing of the operations under control of this apparatus.

25 A fifth important object of the invention is to provide a novel device of this character which is adjustable to enable the device to be applied to various kinds of windmills as now constructed.

With the above and other objects in view as 30 will be hereinafter apparent, the invention consists in general of certain novel details of construction and combinations of parts hereinafter fully described, illustrated in the accompanying drawings and specifically claimed.

35 In the accompanying drawings like characters of reference indicate like parts in the several views, and:

Figure 1 is a side elevation of the invention.

Figure 2 is a plan view thereof.

40 Figure 3 is a section on the line 3—3 of Figure 1.

Figure 4 is a section on the line 4—4 of Figure 1.

In the accompanying drawings, which illustrate one preferred embodiment of the invention, it is to be understood that the right hand end of the device as seen in Figures 1 and 2 will be referred to as the front of the machine and the left hand end of those figures will be termed the rear of the machine.

50 The device is provided with a double A-frame which comprises a pair of front legs 10 and a pair of rear legs 11 which are connected at their upper ends by a single bolt or shaft 12, the front legs at this point lying against the outer faces

of the rear legs. The front legs are provided with alternate short vertical portions 13 offset outwardly with respect to each other from top to bottom and these offset portions are connected by diagonal portions 14. The rear legs are similarly formed of alternate vertical portions 15 and diagonal portions 16. The lower ends of the lowest portions 13 and 15 are bent to extend vertically downwards as at 17 and in these lower ends there is provided a series of vertically spaced bolt openings 18. Vertical leg extensions 19 are provided with similarly spaced bolt holes 20 and are connected to the lower portions 17 by bolts 21 passing through selected bolt holes 18 and passing so that the height of the frame may be 10 adjusted to suit varying conditions in the windmill, the platform of which is shown at 22. Foot angles 23 are provided to connect the bottom ends of the extensions 19 to the platform 22. Longitudinal brace bars 24 are secured to certain of the vertical portions 13 and 15 by bolts 25 15 which run from one leg to the opposite leg and thus form cross-ties for the frame. The members 24 have rearward extensions 26 which are connected by diagonal braces 27 to the lower 20 leg portions 15.

Depending centrally from the shaft 12 is a pendulum hanger 28 which is held from lateral movement on the bolt by collars or washers 29. Diagonal braces 30 secure the lower end of this hanger 28 to the rear legs 11, a cross-tie bolt 31 connecting these braces 30 and said legs. A bolt or shaft 32 connects the braces 30 and the hanger 28 and its outer ends serve to support the upper ends of pendulum stem members 33. The members 27, at their juncture with the legs, are 35 connected to the legs and to each other by a cross-tie bolt 34. Similarly, cross-tie bolts 25 and 35 connect the front legs 10.

Extending longitudinally of the frame along its center line is a cylindrical guide 36 having on its upper side a longitudinal slot 37. This guide is supported at its rear end by a clamping strap 38 carried by the bolt 31 and having its sides gripped on the guide 36 by a clamping bolt 39. 40 A stirrup 40 supports the guide from the front legs 10, being fastened to said legs by bolts 41. Part of the weight of the guide may be taken by the bolts 25. Reciprocably mounted in the guide is a long plunger 42 having a lug 43 projecting upwardly through the slot 37. A bolt 44 pivotally 45 connects the forward ends of a pair of links 45 to the lug 43 and the rear ends of these links are provided with a series of openings 46 and pass between the stem members 33. The members 33 50

are likewise provided with a series of spaced openings 47 and a bolt 48 passes through selected openings 46 and 47 so that the position of the plunger and its stroke, relative to the oscillations of the members 33, may be regulated. The lower ends of the members 33 are provided with longitudinally spaced openings 49. These members 33 may be of any desired length, being shown in the drawings as broken away for this purpose. In fact, the pendulum may extend below the platform 22 to a point near the ground or even into a pit in the ground.

Members 50 extend forwardly from the bolts 41 and are united at their forward ends by a yoke 51. Braces 52 extend forwardly and upwardly from the bolt 35 to meet the members 50, one of the braces being secured to its member 50 by a bolt 53 while a shaft 54 connects the other member 50 and its brace, the shaft being journaled in openings in said member and brace. On the shaft 53 is fixed a gear wheel 55 which is provided with a crank pin 56 connected to the forward end of the plunger by a connecting rod 57. On the shaft 54 is also fixed a crank disc or wheel 58 provided with a crank pin 59 carrying one end of a link 60. The other end of the link 60 is adapted to be connected to the sucker rod 61 of a windmill by a bolt 62.

Depending from the bolt 53 and shaft 54 is a pair of hangers 63 wherein is journaled a shaft 64 and these hangers are connected to the front legs 10 by braces 65. On the shaft 64 is mounted a gear wheel 66 which meshes with the wheel 55 and is provided with a hand crank 67. This wheel is for the purpose of giving the mechanism its initial impulse.

At 68 is a bucket forming the pendulum bob and this bucket is provided with side straps 69 which may be connected to suitable openings 49 of the members 33 by bolts 70. The bob is made in bucket form so that it may be loaded with suitable weight as indicated by the lumps of rock 71 in Fig. 3.

A connecting link 72 is provided at the rear of the plunger so that two of these devices may be connected end to end. Also, a pair of these devices may be arranged side by side, both being connected to the element 60. Furthermore, while not here shown it is obvious that ball or other anti-friction bearings may be used wherever needed or found desirable.

Leaf springs 73 are mounted on the frame in such position as to be engaged by the members 33 when oscillating. This is to absorb any shocks 55 caused by excessive amplitude of oscillation of the pendulum.

In operation, the device is, if necessary, started by turning the wheel 66. The pendulum will now oscillate and the wheels 55 and 58 will rotate. The reciprocation of the sucker-rod 61 will maintain this oscillation. Due to the law of physics governing the oscillation of pendulums the times of the reciprocations of the rod 61 will be kept uniform and sudden puffs of wind or drops in wind pressure will have no practical effect on the speed at which the rod 61 operates.

Obviously, the wheel 58 may be made as a belt wheel and belted to any desired rotary mechanism the speed of which it is desired to govern.

There has thus been provided a simple and efficient device of the kind described and for the purpose specified.

It is obvious that minor changes may be made in the form and construction of the invention 75 without departing from the material spirit there-

of. It is not, therefore, desired to confine the invention to the exact form herein shown and described, but it is desired to include all such as properly come within the scope claimed.

Having thus described the invention, what is claimed as new, is:

1. In a windmill having a reciprocating element, a power controlling device including a supporting frame, a pendulum swingingly supported from said frame, a plunger mounted on said frame and extending longitudinally in the plane of oscillation of the pendulum, plunger operating means connecting the plunger and pendulum, said plunger operating means including a link adapted for connection at selected points 10 of its length to selected points on the pendulum and means for so connecting the link and pendulum, and a linkage connecting the plunger and the reciprocating element of the windmill.

2. In a windmill having a reciprocating element, a power controlling device including a supporting frame, a pendulum swingingly supported from said frame, a plunger mounted on said frame and extending longitudinally in the plane of oscillation of the pendulum, a link having 20 one end connected to said plunger and its other end connected to said pendulum to reciprocate the plunger as the pendulum oscillates, means to connect the link at spaced points in its length to spaced points in the length of the pendulum, 30 and a linkage connecting the plunger and the reciprocating element of the windmill.

3. In a windmill having a reciprocating element, a power controlling device including a supporting frame, a pendulum swingingly supported from said frame, a plunger mounted on said frame and extending longitudinally in the plane of oscillation of the pendulum, a link having one end connected to said plunger and its other end connected to said pendulum to reciprocate the 40 plunger as the pendulum oscillates, means to connect the link at spaced points in its length to spaced points in the length of the pendulum, a shaft journaled in said frame and provided with crank means, a connecting rod connecting said 45 plunger and crank means, and a link connecting said crank means and the reciprocating part of the windmill.

4. In a windmill having a reciprocating element, a power controlling device including a supporting frame, a pendulum swingingly supported from said frame, a plunger mounted on said frame and extending longitudinally in the plane of oscillation of the pendulum, a link having one end connected to said plunger and its other end connected to said pendulum to reciprocate the plunger as the pendulum oscillates, a shaft journaled in said frame, a wheel fixed on said shaft and having a crank-pin projecting therefrom, a connecting rod connecting said plunger and crank-pin, a second wheel fixed on said shaft and having a crank-pin projecting therefrom, and a link having one end connected to the last mentioned crank pin and having its other end adapted for connection to the reciprocating part 65 of the windmill.

5. In a windmill having a reciprocating element, a power controlling device including a supporting frame, a pendulum swingingly supported from said frame, said pendulum including a 70 bucket-like bob for receiving selected weight masses and an extensible stem, and a linkage connecting the pendulum to the reciprocating element of the windmill.

6. In a windmill having a reciprocating ele- 75

ment, a power controlling device including a supporting frame, a pendulum swingingly supported from said frame, said pendulum including a bucket-like bob for receiving selected weight 5 masses and an extensible stem, a plunger mounted on said frame and extending longitudinally in the plane of oscillation of the pendulum, plunger operating means connecting the plunger and pendulum, and a linkage connecting the plunger and 10 the reciprocating element of the windmill.

7. In a windmill having a reciprocating element, a power controlling device including a supporting frame, a pendulum swingingly supported from said frame, said pendulum including a bucket-like bob for receiving selected weight 15 masses and an extensible stem, a plunger mounted on said frame and extending longitudinally in the plane of oscillation of the pendulum, a link having one end connected to said plunger and its 20 other end connected to said pendulum to reciprocate the plunger as the pendulum oscillates, and a linkage connecting the plunger and the reciprocating element of the windmill.

8. In a windmill having a reciprocating element, a power controlling device including a supporting frame, a pendulum swingingly supported from said frame, said pendulum including a bucket-like bob for receiving selected weight 25 masses and an extensible stem, a plunger mounted on said frame and extending longitudinally in the plane of oscillation of the pendulum, a link having one end connected to said plunger and its 30 other end connected to said pendulum to reciprocate the plunger as the pendulum oscillates, a shaft journaled in said frame and provided with 35 crank means, a connecting rod connecting said plunger and crank means, and a link connecting said crank means and the reciprocating part of the windmill.

9. In a windmill having a reciprocating element, a power controlling device including a supporting frame, a pendulum swingingly supported from said frame, said pendulum including a bucket-like bob and an extensible stem, a plunger 40 mounted on said frame and extending longitudinally in the plane of oscillation of the pendulum, a link having one end connected to said plunger and its other end connected to said pendulum to reciprocate the plunger as the pendulum oscillates, a shaft journaled in said frame, a wheel fixed on said shaft and having a crank-pin 45 projecting therefrom, a connecting rod connecting said plunger and crank-pin, a second wheel fixed on said shaft and having a crank-pin 50 projecting therefrom, and a link having one end connected to the last mentioned crank pin and having its other end adapted for connection to the reciprocating part of the windmill.

10. In a windmill having a reciprocating element, a power controlling device including a supporting frame, a pendulum swingingly supported from said frame, a linkage connecting the pendulum to the reciprocating element of the windmill, and spring means supported on the frame at each 60 side of the pendulum for engaging the pendulum to cushion excessive oscillations thereof.

11. In a windmill having a reciprocating element, a power controlling device including a supporting frame, a pendulum swingingly supported 65 from said frame, a plunger mounted on said frame and extending longitudinally in the plane of oscillation of the pendulum, plunger operating means connecting the plunger and pendulum, a linkage connecting the plunger and the reciprocating 70 element of the windmill, and spring means

supported on the frame at each side of the pendulum for engaging the pendulum to cushion excessive oscillations thereof.

12. In a windmill having a reciprocating element, a power controlling device including a supporting frame, a pendulum swingingly supported from said frame, a plunger mounted on said frame and extending longitudinally in the plane of oscillation of the pendulum, a link having one end connected to said plunger and its other end connected to said pendulum to reciprocate the plunger as the pendulum oscillates, a linkage connecting the plunger and the reciprocating element of the windmill, and a spring means supported on the frame at each side of the pendulum 15 for engaging the pendulum to cushion excessive oscillations thereof.

13. In a windmill having a reciprocating element, a power controlling device including a supporting frame, a pendulum swingingly supported 20 from said frame, said pendulum including a bucket-like bob and an extensible stem, a linkage connecting the pendulum to the reciprocating element of the windmill, and spring means supported on the frame at each side of the pendulum 25 for engaging the pendulum to cushion excessive oscillations thereof.

14. In a windmill having a reciprocating element, a power controlling device including a supporting frame, a pendulum swingingly supported 30 from said frame, said pendulum including a bucket-like bob and an extensible stem, a plunger mounted on said frame and extending longitudinally in the plane of oscillation of the pendulum, plunger operating means connecting the plunger 35 and pendulum, a linkage connecting the plunger and the reciprocating element of the windmill, and spring means supported on the frame at each side of the pendulum for engaging the pendulum 40 to cushion excessive oscillations thereof.

15. In a windmill having a reciprocating element, a power controlling device including a supporting frame, a pendulum swingingly supported from said frame, said pendulum including a bucket-like bob and an extensible stem, a plunger 45 mounted on said frame and extending longitudinally in the plane of oscillation of the pendulum, a link having one end connected to said plunger and its other end connected to said pendulum to reciprocate the plunger as the pendulum oscillates, a linkage connecting the plunger and the reciprocating element of the windmill, and spring means supported on the frame at each side of the pendulum 50 for engaging the pendulum to cushion excessive oscillations 55 thereof.

16. In a windmill having a reciprocating element, a power controlling device including a supporting frame, a pendulum swingingly supported from said frame, a plunger mounted on said frame 60 and extending longitudinally in the plane of oscillation of the pendulum, a link having one end connected to said plunger and its other end connected to said pendulum to reciprocate the plunger as the pendulum oscillates, a shaft 65 journaled in said frame, a wheel fixed on said shaft and having a crank-pin projecting therefrom, a connecting rod connecting said plunger and crank-pin, a second wheel fixed on said shaft and having a crank-pin projecting therefrom, a 70 link having one end connected to the last mentioned crank pin and having its other end adapted for connection to the reciprocating part of the windmill, one of said wheels having gear teeth 75 on its periphery to form a gear, a second shaft

in said frame, a gear on said shaft meshing with the first gear, and a crank-handle projecting from the gear on the second shaft.

17. In a windmill having a reciprocating element, a power controlling device including a supporting frame, a pendulum swingingly supported from said frame, said pendulum including a bucket-like bob and an extensible stem, a plunger mounted on said frame and extending longitudinally in the plane of oscillation of the pendulum, a link having one end connected to said plunger and its other end connected to said pendulum to reciprocate the plunger as the pendulum oscillates, a shaft journalled in said

frame, a wheel fixed on said shaft and having a crank-pin projecting therefrom, a connecting rod connecting said plunger and crank-pin, a second wheel fixed on said shaft and having a crank-pin projecting therefrom, a link having one end connected to the last mentioned crank pin and having its other end adapted for connection to the reciprocating part of the windmill, one of said wheels having gear teeth on its periphery to form a gear, a second shaft in said frame, a gear on said shaft meshing with the first gear, and a crank-handle projecting from the gear on the second shaft. 5 10

LUKE S. STRIPLING.
